UNITED STATES PATENT OFFICE.

OSCAR HULSE, OF RONDEBOSCH, CAPE PROVINCE, SOUTH AFRICA.

TYPE OF RAILWAY PASSENGER COACH WITH DOUBLE DECKS.

Application filed December 15, 1924, Serial No. 756,143, and in the Union of South Africa March 23, 1924.

The present invention has reference to improvements in that class of invention known as railway rolling stock and more particularly relates to a rigid railway coach.

5 The invention as its primary aim and object contemplates the provision of a railway coach of a standard size and gauge provided with upper and lower deckings or passageways for increasing the capacity of the 10 coach, the parts being arranged so that the passengers may conveniently enter and leave the coach and reach the seats either on the upper or lower deck.

More particularly the present invention 15 contemplates the provision in a device of the above character of an underslung or well frame which is positioned in spaced relation to the draw bed and between which underslung portion of the frame and the roof of 20 the coach are arranged the upper and lower deckings or platform which in turn support the seats.

More specific objects of the present invention reside in the provision of a railway 25 coach wherein the roofing of the lower seating compartment constitutes the supports for the seats in the upper compartment and a support for the flooring of the passageways in the upper part while the main longitudinal 30 braces are positioned in the body so as to provide backs for the upper seats; in addition the inclined portions of the underslung framework constitutes supports for the steps leading to the lower compartment.

35 Other objects as well as the nature, characteristic features and scope of the invention will be more readily apparent from the following description taken in connection with the accompanying drawings and 40 pointed out in the claims forming a part of this specification.

The invention is clearly illustrated in the accompanying drawings, in which:—

Fig. 1 is a fragmentary longitudinal sectional detail through one-half of the improved railway coach the other half of which is similarly constructed, and

Fig. 2 is a transverse sectional view through the improved coach.

Similar characters of reference are employed in all of the above described views to indicate corresponding parts.

Referring now, more particularly, to the accompanying drawings, there is provided a 15 main rectangular frame embodying side bars 1 and end bars 2 preferably though not

necessarily constructed of channel iron. The respective end portions of the frame are supported by trucks 3 while the medial portion of the frame is underslung to form 60 a well the bottom of which is positioned in closely spaced relation to the draw bed, and the underslung portion of which consists of plurality of channel shaped bars which are indicated by the numeral 4 and arranged in 65 closely spaced relation medially of the frame with the inclined portion 5 connected with a transverse portion 6 in the main frame 1 while similarly constructed underslung portions 7 have their inclined portions 70 connected with the main side bars 1 as shown at 8. The horizontal portions of the bars 4 and 7 support a flooring 9 for the lower compartment while the inclined portions 5 of the bars support centrally arranged steps 10 75 which lead from the main platforms 11 on the truck supported end portions of the main frame and these platforms are preferably in alignment with the station platform so that passengers may conveniently 80 enter the coach.

A body 12 of the standard size is mounted on the truck supported underslung frame and is provided adjacent the platforms 11 with doors 13 and 14 for permitting of the 85 entrance and discharging of the passengers and in addition has a central aisle communicating with a connecting vestibule 15 for attachment with another coach. Transverse seats 16 are arranged on opposite sides of 90 the aisle on the platforms 11 and in addition the sides of the body are provided with windows 17 and other conveniences for the passengers such as racks 18 and lights 19.

Rising vertically from the inclined portion 5 are transverse reinforcing and supporting partitions 20 to separate the end compartments 21 from the lower and upper compartments 22 and 23 respectively. These partitions 20 are provided with a central doorway 24 arranged about the stairs 10 to allow the passengers to enter the lower compartment 22. The latter compartment is fitted on opposite sides with longitudinally arranged seats 25 which extend throughout 95 the length of the compartment 23 and which face each other while in addition this lower portion is provided with windows 26.

Arranged vertically and positioned in longitudinal alignment are two rows of pillars 110 27. These pillars are arranged adjacent the seats and between the two rows a central pas-

sageway is provided which communicates with the steps 10. A roofing 28 is provided for the lower compartment while the central portion 29 is arched so that passengers may 5 walk in an upright position through the lower compartment to and from the seats. Lights 30 are mounted in the top of the arched portion and the latter is also fitted with hangers 31 for the convenience of the 10 passengers. The horizontal side portions of the roofing together with the pillars and the side portions 31' of the car constitute supports for the floorings 32 for the upper compartment 23 while the upper seats 33 15 which extend throughout the length of the upper compartment are arranged back to back and face the aisles provided by the floorings 32 on opposite sides of the car body. In order to reinforce the body, longitudinal beams 34 are arranged immediately 20 above the arched portion 29 of the roofing and secured to the partitions 20. These portions are slightly inclined toward each other and constitute the backs of the seats 25 in the upper compartment while the respective ends are cut away as at 35 to align with the upper edge of the doorways 24 this inclined portion being positioned immediately above the steps 10 so as to facilitate passengers entering and leaving the lower compartment by way of the steps. The partitions 20 are in addition provided with doorways 36 to permit of entrance to the upper compartments while other stairs 37 lead 30 from the aisles 32 and doorways 36 to the platforms 11. Rails 38 are provided adjacent both the stairs 10 and 37.

In order to further reinforce the roof vertical bars 39 are arranged between the 40 beams 34 and the roof 40 of the body while the lights 41 and hangers 42 are arranged on the inside of the roof 40 for the convenience of the passengers in the upper compartment. Windows 43 are also arranged in 45 the walls of the coach body for lighting and ventilating the upper compartment.

Attention is particularly directed to the fact that the legs of the seats 33 are arranged in alignment with the rows of pillars 27 while the upper portion of the arched portions 29 serves to coact with the beams 34 in supporting the main portion of the upper seats. It is also to be noted that the roofing 28 with its arched portion 29 as well 55 as the floors 32 constitute horizontal partition members which divide the upper and lower compartments over the underslung portion.

Attention is also directed to the fact that 60 the roof and side walls of the body or coach are in continuous unbroken alignment from end to end. By the terms "size" and "gauge" it is to be understood that these terms are intended to cover a railway coach in which 65 the height and width is the same as ordinary

railway coaches at present in use on the railroads in this country, the particular advantage being in the provision of a superposed seating compartment in a railway coach the over-all height of which at all 70 points is the same as a standard railway coach so that the present coach may be used on all railway lines so as to pass through tunnels and under low bridges etc.

It is believed in view of the foregoing 75 that a further detailed description of the operation of the invention is entirely unnecessary. Likewise it is believed that the advantages of the invention will be readily apparent.

Having thus fully described the invention what is claimed as new and desired to be secured by Letters Patent is:—

1. A railway coach including a body of the standard size and gauge provided with 80 entrance and exit compartments at the respective ends and also provided with an underslung medial portion having superposed seating compartments, the walls and roof of the body at the ends and middle 85 being respectfully in continuous unbroken alignment with each other, and means for permitting access of passengers to either of the superposed compartments from the end compartments.

2. A railway coach of the character described, a rectangular frame, trucks at the respective ends thereof, an underslung frame structure situated between the trucks and including inclined portions, a body of the 90 standard gauge size carried by the frame, combined passenger and entrance and exit compartments at the respective ends of the body, and superposed compartments positioned over the underslung portion and communicating with the end compartments.

3. A railway coach as claimed in claim 1, wherein steps are provided between the end compartments and the lower compartments and are supported on inclined portions of the underslung part of the frame.

4. A railway coach as claimed in claim 2, wherein reinforcing and supporting partitions are arranged transversely and vertically in the body between the end compartments and the superposed compartments and provided with door-ways for permitting the passengers passing from the end compartments into either the upper or lower compartments.

5. A railway coach including a body provided with an underslung portion having admission and exit compartments at the respective ends thereof and superposed compartments at the underslung portion, partitions separating the end compartments from the superposed compartments and provided with doorways, steps leading from the end compartments respectively to the upper and lower compartments, seats arranged on op-

- posite sides and facing each other in the lower compartment, seats arranged back to back and longitudinally of the upper compartment, and longitudinal reinforcing beams arranged between the partitions and forming supports for the backs of the seats in the upper compartments. 5
6. A railway coach, a frame provided with an underslung portion, a body carried by the frame, end compartments in said body, a horizontally arranged and longitudinally extending partition member medially of the height of the body over the underslung portion of the frame and dividing the same into superposed compartments, the medial portion of said member being arched forming a roofing for the passageway in the lower compartment, seats on opposite sides of the lower compartments and facing each other, the side portions of the horizontal member constituting the floor of the upper compartment, seats arranged back to back in the upper compartment and supported on the arched portion of the member, vertical transverse partitions separating the end compartments from the superposed compartments, and provided with door-ways for establishing communication therebetween and steps leading from the end compartments to the upper and lower compartments. 10
7. A railway coach as claimed in claim 6, wherein longitudinal beams are arranged between the vertical partitions and constitute supports for the backs of the seats in the upper compartment. 15
8. A railway coach as claimed in claim 6, wherein longitudinal beams are arranged between the vertical partitions and constitute supports for the backs of the seats in the upper compartment, and vertically disposed rods between the roof of the body and the longitudinal beams. 20
9. A railway coach as claimed in claim 6, wherein a plurality of pillars are arranged vertically within the lower compartment in spaced parallel rows adjacent the seats leaving a central aisle therebetween, and the pillars acting to sustain the weight of the forward portions of the seats in the upper compartment. 25
10. A railway coach of the standard size and gauge including a frame having a medial underslung portion, a body for the frame, vertical partitions separating the body into a large medial compartment over the underslung portion and relatively small compartments at the ends of the body, a horizontal partition member between the vertical partitions and separating the medial compartment into upper and lower compartments, seats arranged in all of the compartments and steps arranged between the end compartments and the upper and lower compartments. 30
11. A railway coach of the standard size and gauge provided with end admission and exit compartments and having the medial portion underslung and provided with superposed compartments arranged in communication with the end compartments, and the outside walls and roof of the coach being in continuous unbroken alignment throughout the length thereof. 35
12. A railway coach of the standard size and gauge provided with combined passenger and admission and exit end compartments and having the medial portion underslung and provided with superposed compartments arranged in communication with the end compartments, seats arranged in all of the compartments and steps arranged between the end compartments and the upper and lower compartments. 40
13. A railway coach of the standard size and gauge provided with combined passenger and admission and exit end compartments and having the medial portion underslung and provided with superposed compartments arranged in communication with the end compartments, seats arranged in all of the compartments, steps arranged between the end compartments and the upper and lower compartments, the seats in the lower compartment being arranged on opposite sides of the compartment and facing each other, the seats in the upper compartment being arranged back to back and a partition between the upper and lower compartments having the medial portion arched transversely forming a roofing for the aisle in the lower compartment and a support for the seats in the upper compartment. 45
14. A railway coach as claimed in claim 13, wherein longitudinal reinforcing beams are arranged between the vertical partitions and constitute supports for the backs of the seats in the upper compartment and having the respective ends cut away at points over the steps between the end compartments and the lower compartment. 50
15. A railway coach of standard gauge and size having the medial portion underslung, a horizontal partition member in the medial portion dividing the same into upper and lower compartments, seats in the compartments, and the medial portion of the partition member being arched transversely to permit of passengers to stand erect in the lower compartment and also form a support for the seats in the upper compartment and combined passenger and entrance and exit compartments at the ends of the coach and arranged in communication with the upper and lower compartments. 55
16. In a railway coach of the character described a main rectangular frame, trucks supporting the ends thereof, a plurality of bars forming an underslung well structure suspended from the main frame and positioned between the trucks, and a body having 60

a continuous unbroken roof and side walls carried by the main frame and the underslung structure and provided with combined passenger and admission and exit compartments positioned over the ends of the main frame and superposed passenger receiving compartments positioned over the underslung structure.

17. A railway coach as claimed in claim 10 16, wherein vertical transverse partitions are arranged adjacent the ends of the body to provide the end compartments and are provided with doorways to establish communication with the superposed compartments. 15

18. A railway coach as claimed in claim 16, wherein the end portions of the bars 20 forming the underslung portion are inclined and steps supported on the inclined portion of the bars for permitting passengers to pass from the end compartments to the lower compartments.

19. A railway car of substantially standard dimensions, including a pair of trucks and a body supported upon and having its central portion extending downwardly between said trucks, and a deck within said car 30 and having its ends terminating adjacent the ends of said central portion, the roof of said car being spaced from the floor and deck thereof, and the deck being spaced from the floor of the central portion thereof 35 to an extent to provide adequate head room.

20. A railroad car of substantially standard dimensions, including a pair of trucks and a body supported upon and having its central portion extending downwardly be-

tween said trucks, and a deck within the 40 central portion of said car and having its ends terminating in planes short of the planes into which the ends of said portion extend, the said deck occupying a horizontal plane above that occupied by the car ends, 45 and stairs leading from said car ends to the floor of said deck and central car portion.

21. A railroad car of substantially standard dimensions, including a pair of trucks and a body supported upon and having its 50 central portion extending downwardly between said trucks, a deck within said central car portion and having one of its ends terminating in a plane short of that into which the corresponding end of the central car 55 portion extends, said deck occupying a plane above the horizontal plane occupied by the car ends, and steps leading from one of said car ends upwardly to the corresponding end of said deck.

22. A railroad car of substantially standard dimensions, including a pair of trucks and a body supported upon and having its central portion extending downwardly between said trucks, a deck within the central 65 portion of said car and in a plane above the end portions thereof, and stairways leading from the inner ends of said end portions to the outer ends of the floors of said deck and the suspended portion, said latter portion, deck and stairways being arranged in the form of an irregular hexagon having parallel sides, the ends of said car extending substantially in line with the side apices of said hexagon.

In testimony whereof I have affixed my signature.

OSCAR HULSE.
